EYE PROTECTOR

Edward M. Splaine, Southbridge, Mass., assignor
to American Optical Company, Southbridge,
Mass., a voluntary association of Massachusetts

Application September 7, 1944, Serial No. 553,014

2 Claims. (Cl. 2-14)

1

This invention relates to improvements in eye protectors and has particular reference to a novel and improved construction of protector embodying eyecups for use in the industries.

One of the principal objects of the invention is to provide a device of this character which shall satisfactorily protect the eyes from flying particles and the like and at the same time permit free and clear lateral vision when the protector is in position on the face.

Another object is to provide an eye protector of the above character with eyecups each having an opening in the side wall thereof covered with a shield having a plurality of perforations therein, with the perforated area of the shield cupped outwardly to afford means for ventilating the eyecups and to increase the ventilated area internally of the eyecups and with said cupped portion being more resistant to impact and also enabling the wearer to have a wider field of lateral vision.

Another object is to provide side shields of the above character which will allow air to flow in a direction substantially transversely of the inner surfaces of said shields and thereby afford greater ventilation.

Another object is to provide eye protectors of the above character with means adjacent the lenses for preventing the fogging of said lenses during use.

Other objects and advantages of the invention will become apparent from the following description taken in connection with the accompanying drawings and it will be apparent that many changes may be made in the details of construction and arrangement of parts without departing from the spirit of the invention as expressed in the accompanying claims. I, therefore, do not wish to be limited to the exact details of construction and arrangement of parts as the preferred form only has been given by way of illustration.

Referring to the drawings:

Fig. 1 is a front elevational view of the device embodying the invention;

Fig. 2 is a side elevational view of said device; and

Fig. 3 is an enlarged sectional view taken as on line 3-3 of Fig. 1 and looking in the direction indicated by the arrows.

Providing goggles or eye protectors of the character described with perforated side shields functioning as baffle means overlying an opening in the side wall of the eyecup is not new in the art. Such prior art side shields, however, were in

2

most instances formed from flat sheet material and were merely placed in overlying relation with the opening substantially in the plane of the outer surface of the eyecup. Such prior art side shields, in some instances, would afford lateral vision through the perforations, but such vision was restricted to the direction of the axis of the openings in said relatively flat plane.

Further difficulty has been encountered with prior art goggles of this nature in that the side shields were not sufficiently resistant to impact and the direction of flow of the air inwardly of the goggles and the area internally of the goggles was not sufficient to introduce the proper ventilation.

One of the principal objects, therefore, of the present invention is to overcome all of the above difficulties in an extremely simple, efficient and inexpensive manner through the forming of a side shield with a central cupped or outwardly bulged portion with the said shield having openings in the side walls of said cupped or bulged portion whereby air may enter the openings in the side walls and traverse the inner surface of the cupped or bulged portion substantially laterally thereof and with said openings in the side walls affording increased vision in a direction rearwardly of the eyecup as indicated by the arrows A and in a direction forwardly of the eyecup as indicated by the arrows B as well as affording lateral vision as indicated by the arrows C. This increased rearward and forward vision greatly increases the area of lateral vision through the side shield while the outward bulged or cupped portion increases the ventilated area internally of the goggle and renders the side shield more resistant to impact.

Referring more particularly to the drawings wherein like characters of reference designate like parts throughout the several views, the device embodying the invention comprises a pair of eyecups 4 having a face engaging edge portion 5 shaped substantially to the contour shape of the face about the eyes. The eyecups are preferably formed of a non-metallic material resistant to heat and heat conduction. The said eyecups 4 are each provided with a forward edge 6 on which a suitable lens 7 may be seated. The said lens is retained on said edge through the provision of suitable screw threads or the like 8 adjacent said edge and a lens retaining ring 9 threadedly connected with said screw threads. The lens supporting edge 6 is provided with a plurality of slots 10 extending throughout the thickness of the walls of the eyecups in a direc-

tion oblique to the tangency of said adjacent inner and outer surface portions and extend substantially throughout the entire circumference of said edge in progressively spaced relation with each other. The lens retaining ring 9 is provided with a plurality of spaced circumferential slots 11 communicating with said slots 10. The eyecups are provided internally thereof and adjacent the slotted lens retaining edge 6 with a reinforcing ring 12 preferably formed of metal. This ring is seated in place during the molding of the eyecup to the shape desired. The lens retaining ring 9 is also preferably formed of relatively thin material having the threaded portion thereof preferably formed by a rolling process and with an inwardly deflected lip 13 adapted to engage a bevelled edge 14 formed on the contour of the lens.

Each of the eyecups is formed with an opening 15 in the temporal wall portion thereof and extending throughout the major area of said wall. The contour of the opening outwardly of the eyecup is provided with a sunken seat or shouldered recess 16 shaped to receive the contour edge portion 17 of the side shield 18. The said side shield 18 is provided with a plurality of vent openings 19 therein and extending substantially throughout the area of the shield overlying the opening 15 with said area being cupped or bulged outwardly as shown best in Fig. 3. The outwardly cupping or bulging of the shield causes the shield to have side wall portions 20 and 21 with openings 19 therein. This outward cupping or bulging of the side shield increases the ventilated area internally of the eyecup and also permits vision through the openings 19 in the front wall portion 20 in the direction indicated by the arrows B and simultaneously increases lateral vision in the direction of the arrows A through the openings 19 in the rear side wall portion 21.

It is also to be noted that air may enter the said openings 19 in the front and rear walls 20 and 21 in the direction of the arrows 22 and 23 as well as through the openings 19 in the direction of the arrows C thereby permitting air to traverse the inner surface of the bulged portion substantially laterally of said inner surface depending upon the direction of flow of the current of air to which the eyecups are exposed during use. If the current of air is flowing in a rearward direction, the air will enter in the direction of the arrows 22 and will be exhausted through the openings in the rear wall portion 21. On the other hand if the current of air is from a direction rearwardly of the goggle, air will enter the openings 19 through the rear wall 21 in the direction of the arrows 23 and will be exhausted through the openings 19 in the front wall portion 20 thereby affording a ventilating action not obtained with prior art flat type side shields.

The said side shields 18 are secured to the eyecups by rivets or the like 24. The temporal sides of the eyecups are each provided with a rearwardly extending end 25 having an opening 26 therein through which a suitable headband or the like 27 is threaded. The said headband 27 is provided with enlarged ends 28 for anchoring the said headband to the rearwardly extending portions 25.

The eyecups are preferably joined with each other by a flexible ball-chain member 29 having its ends extended through openings 30 formed in the nasal wall portions of the eyecups. The ends 29 are secured or anchored with the eyecups by pivoted clips 31 having a slotted portion 32 adapt-

ed to straddle the link portions 33 connecting the ball portions 29 together. The said clip 31 is pivoted to the eyecup as illustrated at 34. The portion of the chain intermediate the eyecups is 5 preferably covered by a tubular member 35 preferably formed of heat resistant material.

From the foregoing description it will be seen that simple, efficient and economical means have been provided in an extremely efficient and inexpensive manner. The outward bulging or cupping of the side shields greatly increases the strength of the said shields against impact and permits relatively rough usage of the goggle without danger of injury to said side shields.

15 I claim:

1. In a device of the character described an eyecup member having an edge portion shaped to engage the face and having a forwardly extending wall portion terminating in an outer supporting edge, said wall portion, on the temporal side thereof, having an opening therein, and a shield overlying said opening, said shield having a centrally disposed dome-like portion cupped outwardly from the plane of its surrounding outer edge portion and shaped substantially to the outer contour shape of the opening and extending substantially throughout the area of said opening, said outer edge portion of the shield constituting a flange-like portion angularly disposed with respect to the side walls of the dome-like portion and lying substantially parallel with the top of said dome-like portion, said flange-like portion being shaped substantially to the contour of the adjacent outer wall of the eyecup surrounding the opening and to fit in contiguous relation therewith, said dome-like portion having spaced openings extending substantially throughout the area thereof with some of said openings lying in the side walls of the dome-like portion and being so disposed relative to each other as to afford increased lateral vision and simultaneously introduce ventilation in a direction transversely of the inner surface of the dome-like portion, and means connecting said flange-like portion with said eyecup member.

2. In a device of the character described an eyecup member having an edge portion shaped to engage the face and having a forwardly extending wall portion terminating in an outer supporting edge, said wall portion, on the temporal side thereof, having an opening therein, and a shield overlying said opening, said shield having a centrally disposed dome-like portion cupped outwardly from the plane of its surrounding outer edge portion substantially to the outer contour shape of the opening and extending substantially throughout the area of said opening, said outer edge portion of the shield constituting a flange-like portion angularly disposed with respect to the side walls of the dome-like portion and lying substantially parallel with the top of said dome-like portion, said flange-like portion being shaped substantially to the contour of the adjacent outer wall of the eyecup surrounding the opening and to fit in contiguous relation therewith, said dome-like portion having spaced openings extending substantially throughout the area thereof with some of said openings lying in the side walls of the dome-like portion and being so disposed relative to each other as to afford increased lateral vision and simultaneously introduce ventilation in a direction transversely of the inner surface of the dome-like portion, said wall portion further having a shouldered recess about the edge of said 75 opening with the flange-like portion of the shield

lying within said shouldered recess and means
securing said flange-like portion in said position.
